BOREHOLE WASHING DEVICE

Allen D. Garrison, Houston, Tex., assignor to
 Texaco Development Corporation, New York,
 N. Y., a corporation of Delaware

Application January 10, 1948, Serial No. 1,618

1 Claim. (Cl. 166—18)

1 This invention relates to washing devices for bore holes or wells, and more particularly to a device through the use of which a stream of washing fluid will be caused to pass through restricted areas or zones in intimate contact with the material which it is desired to remove from the walls of the hole, such as drilling mud cake. The principal object of the invention is to provide a device of this kind which, when attached to the lower end of a string of tubing or drill pipe can be expanded to restrict the annular space between the tubing and the walls of the hole without the necessity of valves or other elements requiring control from the surface.

As is well known, when drilling a bore hole a fluid such as mud is commonly used for carrying the cuttings upwardly to the surface. Another function of the fluid is to plaster and to form a cake of the mud on the inner surfaces of the hole to prevent sloughing of the formation walls into the hole, to prevent water from filtering into the hole, etc. After the casing has been set in the hole, it is desirable to remove the mud cake from the walls of the oil bearing formation and this has frequently proven quite difficult. It has been found that where gravel has been packed between the flow tubing and the walls of the producing formation, water or other liquid forced downwardly to the bottom of the tubing string and then upwardly through the gravel pack tends to wash the mud from the formation walls effectively, this being due to the fact that the restricted passages within the gravel and between the gravel particles and the walls of the formation increase the velocity of the liquid. Obviously when the water issuing from the lower end of the tubing string is permitted to pass upwardly through an annular space as large as that between the tubing and the walls of the hole the velocity is greatly reduced and much of the water does not come in contact with the mud cake with sufficient velocity to remove the mud.

In accordance with this invention an expandable balloon-like member is affixed to the lower end of a tubing or drill pipe string with means for maintaining the member normally in its longitudinally extended, horizontally contracted position. When liquid is forced downwardly through the string a portion will pass outwardly at the bottom of the string and will then pass upwardly through the space between the walls of the hole and the retracted member. Another portion, however, will pass from the tubing string into the member to cause it to expand laterally

5 toward the walls of the hole and this will concentrate the flow of the washing liquid past the mud cake, this restricted area being adjacent the mud cake on the formation walls. The outer surface of the expandable member is preferably provided with spines or other pointed elements which tend to penetrate the mud cake so as to break it up. The outer surface is also provided with a plurality of vanes or baffles which engage the formation walls so as to hold the body of the expandable member in spaced relation to the walls without materially interfering with the flow of liquid. In this manner the washing liquid passing outwardly through the bottom of the 10 tubing string is forced upwardly through the vanes and spines so as to effectively wash the mud cake from the walls. The device can be lowered or raised in steps while being retracted and expanded so that all of the surface of the 15 formation walls will be cleaned of the mud cake, or it can be lowered or raised continuously while the washing fluid is flowing, for the same purpose. For a better understanding of the invention reference may be had to the accompanying drawing, in which

Fig. 1 is a vertical sectional elevation showing the washing device in retracted position being lowered through the casing;

Fig. 2 is a cross-section on the line 2—2 of 20 Fig. 1;

Fig. 3 is a view similar to Fig. 1 but showing the washing element in its expanded or cleaning position against the formation walls, and

Fig. 4 is a cross-section on the line 4—4 of 25 Fig. 3.

Referring to the drawing, a section of a bore hole 10 is shown as provided with a casing 12 cemented in place, as indicated diagrammatically at 14. With reference to Fig. 3, the lower portion 40 of the bore hole is illustrated as penetrating a producing formation 16 and on the walls of the producing formation below the casing 12 is shown a mud cake or layer 18, the mud having been deposited during the drilling operation.

45 A pipe string 20 which may be tubing, liner or drill pipe has attached to its lower end a pipe section 22 having a few wall perforations 24 and a somewhat restricted opening 27 at its bottom. An expandable balloon-like member 26 of rubber or other flexible material and preferably somewhat elongated in shape is firmly attached at its upper end to the upper exterior of the pipe section 22 as by cementing to or squeezing between rings 28, threaded or welded onto the pipe. The 50 lower end of the member 26 is shown as provided

with an opening, the edge of which is disposed in a channeled ring member 30 adapted to slide loosely upon the exterior of the pipe 22. Within the member 26 and surrounding the pipe section 22 is a coiled compression spring 32 adapted to force the lower end of the member 26 downwardly, away from the upper end so that the member will be longitudinally extended and laterally retracted when the device is being run into the bore hole, as shown in Fig. 1.

The outer side surfaces of the expansible member 26 are provided with a plurality of spines or spikes 34 which may be of rubber, metal, or other suitable material. Disposed longitudinally along and in spaced relation about the exterior surface of the member 26 are a plurality of vanes or baffles 36 which also may be of rubber or metal, the purpose of which is to hold the outer surface of the expansible member slightly spaced from the walls of the hole when the member is in its expanded position to prevent the member 26 from "packing off" the annular space. If the vanes 36 are of rubber they may comprise continuous strips extending up and down the sides of the expansible member. If, however, the vanes are of metal or other non-flexible material, they may be formed in a plurality of shorter sections slightly separated as indicated by spaces 38.

As shown in Figures 1 and 2, when there is no fluid under pressure within the tubing 20, the member 26 will remain in its laterally contracted position due to the pressure exerted by the spring 32. In this position, the device can be easily run into a cased hole as shown in Fig. 1 to a position below the bottom of the casing as shown in Fig. 3. Assuming that water is used as the washing fluid, this water being forced downwardly through the tubing string 20 will pass outwardly through the bottom opening 27 and then upwardly as indicated by the arrows 40 in Fig. 3. At the same time a portion of the water will pass outwardly through the perforations 24 into the expansible member 26 causing the latter to expand laterally, pulling upwardly the ring 30. The water entering the expanded member is indicated by the arrows 42. The spring 32 will, of course, be compressed somewhat due to the vertical shortening of the expansible member. The studs, or spines, 34 will penetrate the mud cake 18 while the vanes 36 will come to rest against the walls of the formation 16, thus maintaining a restricted annular space between the outer surface of the member 26 and the formation walls. The spines 34 and the vanes 36 will tend to break up the mud cake 18 and will also provide some turbulence of flow of the wash water in passing upwardly around the sides of the expansible member. In this manner the mud cake will be quickly and completely removed from the formation walls, the removed mud flowing upwardly to the surface with the returning wash water. If desired the vanes 36 may be disposed in a spiral formation up and down the outer surface of the member 26.

As stated hereinbefore, after a section of the formation wall has been cleaned the tubing string 20 may be lowered or raised a distance equal to the expanded length of the member 26. In doing

this the flow of water downwardly through the tubing 20 may be stopped, thus permitting the member 26 to return to its retracted condition after which it will again be expanded when the device has been raised or lowered to the next cleaning position. If desired, the member 26 may remain in its expanded position while the tubing 20 is moved continuously up or down along the formation walls, the spines 34 serving to abrade and scrape the mud cake from the walls at the same time the mud is being washed away by the upwardly flowing water.

Although the device has been described with particular reference to the cleaning of mud cake other uses will be apparent. For example, a similar expansible member may be disposed about the casing at some point above the conventional cementing shoe. When expanded the cement would be forced to the outside of the hole and by thus increasing the velocity of the rising cement slurry the wall of the hole would be cleaned of mud cake to insure a uniform bond of the cement against the formation. In this instance the device would in all probability be left in the hole after the cementing operation.

Obviously many modifications and variations of the invention, as hereinbefore set forth, may be made without departing from the spirit and scope thereof, and therefore only such limitations should be imposed as are indicated in the appended claim.

I claim:

A bore hole washing device comprising a string of tubing adapted to be lowered into said hole, the bottom end of said tubing being provided with a downwardly directed opening smaller in diameter than the interior of said tubing, an expansible balloon-like member encircling said tubing near its lower end, one end of said member being rigidly attached to said tubing and the other end having loose, sliding engagement with the outer surface of the tubing, a plurality of flexible substantially vertical vanes projecting outwardly from the outer surface of said member, a plurality of spines also projecting outwardly from the outer surface of said member between said vanes, and means for normally holding said member in horizontally retracted, vertically extended position, the portion of said tubing within said member being provided with an opening and the arrangement being such that when fluid under pressure flows downwardly through said tubing string a portion of it will pass through said last-mentioned opening into said balloon-like member to expand it horizontally so that said vanes and spines will engage the walls of the hole.
